(57) CLAIM

The ornamental design for a file cabinet, as shown and described.

DESCRIPTION

FIG. 1 is a perspective view of a file cabinet showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of open state; and,

FIG. 9 is an enlarged view of portion of FIG. 8.

The dashed or broken lines shown in the drawings depict portions of the file cabinet in which the design is embodied that form no part of the claimed design.
